FISHING LURE

Harry G. Stoebener, 114 Hodil Terrace, Pittsburgh, Pa.

Filed Feb. 24, 1959, Ser. No. 54,701

Term of patent 14 years

(Cl. D31—4)

Fig.1.

Fig.2.

Fig.3.

FIG. 1 is a front, perspective view of a fishing lure showing my new design;

FIG. 2 is a rear, perspective view thereof, and
FIG. 3 is a side, elevational view thereof.

I claim:

The ornamental design for a fishing lure, substantially as shown.
